UNITED STATES PATENT OFFICE

HERBERT S. MCCORMICK, OF ALAMEDA, CALIFORNIA, ASSIGNOR TO JOSEPH N. BORROUGHS, OF OAKLAND, CALIFORNIA

TOWEL CABINET

Application filed November 11, 1929. Serial No. 406,294.

This invention is for a towel cabinet provided with a feeding device which is adapted to consecutively present predetermined lengths of a roll of toweling in position for use within an opening in the cabinet.

The main object of the invention is to provide a device of the character outlined which will successively present clean portions of a roll of toweling in measured amount at an opening in a cabinet, which opening is normally closed by a sliding door, the towel being fed and door opened simultaneously by depression of a treadle, the door being closed on release of the treadle.

Another object of the invention is to provide a device of the character outlined in which the used or soiled portion of the towel is concealed by automatic closure of the opening through which the portion of toweling is presented for use.

A further object of the invention is to provide a device of the type outlined wherein the soiled portion of the towel will be deposited in the lower portion of the cabinet, while simultaneously presenting a clean portion of toweling in registry with the opening and uncovering the opening, the operation being conducted by a single depression of a treadle.

Other objects and advantages of the invention will become apparent as the following description is read on the drawings forming a part of this specification.

The invention consists primarily of a towel cabinet provided with a rack for freely supporting a roll of toweling, which is threaded between and about a plurality of rollers, presenting a loop of toweling at an opening in the front of the cabinet, a roller disposed in the loop, means for feeding clean portions of toweling in predetermined lengths, a closure for the opening, means for opening the closure, means for retaining the loop roller in lower-most position until the closure is substantially fully opened and at which point the retaining means is released and the roller automatically moves to an upper location and means for closing the opening, all of which operations are actuated by depression and release of a treadle or lever.

The invention is adequately illustrated in the accompanying drawings in which

Fig. 1 is a perspective view of the towel cabinet, showing the portion of towel exposed through the opening in the front wall;

Fig. 2 is a transverse sectional elevation of the cabinet showing the towel feeding rolls and method of threading the towel and is taken on the median line of the cabinet;

Fig. 3 is a transverse sectional elevation of the cabinet and the actuating mechanism taken adjacent one side of the cabinet;

Fig. 4 is an enlarged detail view of the loop roller guiding and actuating means;

Fig. 5 is a section taken on line 5—5 of Fig. 4;

Fig. 6 is an enlarged detail of the roller guiding and retaining means;

Fig. 7 is a front elevation of the feed rollers and actuating mechanism;

Fig. 8 is a vertical sectional view taken on line 8—8 of Fig. 7;

Fig. 9 is a detail view partly in section of one of the operating pulleys.

Similar reference characters are used to indicate similar parts throughout the several views.

A cabinet 1 is formed with sides 2 and 3, and front 5 in which an opening 26 is provided and which is normally closed by a vertically sliding door 47 at the lower end, and by a hinged door 4 at the upper end, door 47 being slidably mounted in grooves 35 formed in the inner edges of the side panels 40.

A towel basket 6 is supported adjacent the top of the cabinet by cooperation of the ends of the longitudinal top edge members 64 with transverse cleats 7 fixed to sides 2 and 3, and is adapted to freely receive a roll of toweling 15, the end 65 of which is threaded over the rearward member 64.

The feeding mechanism consists of two pair of coacting rollers one of each pair being positively driven, and consist of longitudinally corrugated soft rubber covered rollers 17 and 24, and plain rollers 18 and 23. Rollers 18 and 24 are idle rollers while 17 and 23 are positively driven, all four rollers being rotatably mounted in a frame and between a pair of spaced plates 12 and 13 forming one

side and the intermediate member of the frame. Slots 21 are provided in plates 12 and 13 in which the journals of rollers 18 and 24 are rotatable, and slideable radially relative to rollers 17 and 23, and are resiliently urged toward these rollers by leaf springs 22 cooperating with the far side of the journals. The journals of rollers 17 and 23 extend through and beyond plate 13 and have fixedly mounted on their outer ends sprockets 39 and 41 which are of equal size.

The frame 11 consists of side plates 12 and 14 and intermediate plate 13, plates 12 and 14 being flanged at top and bottom as indicated at 69 and 70. The plates are secured together in spaced relation by a plurality of rods 16 and 8, spacers 10 providing separators between plates 13 and 14. Rods 16 are shouldered at both ends to act as spacers between plates 12 and 13. A rigid frame is thus provided.

The driving means for the rollers consists of sprockets 39 and 41 fixed on the journals of rollers 17 and 23, and a sprocket 31 which is rotatably mounted on a fixed shaft 28 which also acts as a spacer and tie between plates 13 and 14 and which is secured by the nuts 29. A chain 42 cooperates with the three sprockets 31, 39 and 41 and drives these sprockets in the same direction, the driving being done by sprocket 31 which is of larger diameter than sprockets 39 and 41.

The driving means for sprocket 31 consists of a spring actuated pawl 38 which engages a notch 33 in a hub extension 32 on sprocket 31, the pawl being mounted on a quadruple pulley 34 in cooperative relation to the notch, as indicated in Fig. 9.

Pulley 34 is rotatably mounted on shaft 28 and is provided with two grooves forming pulleys 37 and 48 of equal and large diameter, and two grooves forming pulleys 44 and 45 of equal and small diameter, each section or pulley having fastening means for a tape, as indicated in Fig. 9, and which consists of a recess 19 formed inwardly from the groove and having a transverse pin 59 secured therein, which cooperates with an eye formed at the end of the tape. Pulleys 37 and 48 have pins 59 in alignment as indicated at 74, Fig. 8. Pulleys 44 and 45 are oppositely connected as indicated at 43 and 62 but in radial alignment with connection 74. Tapes 66 and 71 are oppositely secured in pulleys 37 and 48, being wound once about the pulleys but in opposite directions. Tapes 56 and 61 are secured in pulleys 44 and 45 at opposite points 43 and 62 and wound once about the pulleys in the same direction.

The entire unit described is removably mounted on angle rails 9 as shown in Fig. 7.

The door operating mechanism consists of tapes 66 and 71, the opposite ends of which are respectively connected to the bottom and top of sliding door 47 as indicated at 68 and

73, tape 66 being looped and guided by an idler pulley 67 which is mounted in a bracket 46 secured to side wall 3, and tape 71 is looped and guided by a pulley 72 mounted in a bracket 75 secured to the top of the cabinet. As the tapes are oppositely wound on the pulleys, rotation of the pulleys causes coincident retraction of one tape and advance of the other.

The driving mechanism consists of tapes 56 and 61 which are secured in pulleys 44 and 45 at 62 and 43, tape 56 having its opposite end connected at 57 to a treadle lever 51 and being intermediately guided by an idler pulley 58 mounted in a bracket 36 which is secured to side wall 3 of the cabinet. Tape 61 has its other end secured to a tension spring 63 which has its opposite end secured at 76 to the wall of cabinet 1. Lever 51 forms a part of treadle 50 which consists of two levers 51 transversely connected at their outer ends by means of a transverse rod 54, the inner ends being pivoted to side walls 2 and 3 as indicated at 52, levers 51 extending through slots 53 formed in the front panel 90 of the cabinet.

The towel tensioning device consists of a spring actuated roller 27 which is provided at its opposite ends with the usual flat end spring actuated shaft 77, and fixed circular journals which are slidably retained in grooves 78 formed in cleats 79 which are secured to side walls 2 and 3. Affixed adjacent each end of roller 27 are grooved pulleys 82 to which are secured cords 83 which are adapted to be wound about the pulley as the roller 27 moves upwardly, the opposite end of the cords 83 being secured to panels 40 as indicated at 55. Brackets 81 are secured to door 47 and cooperate with the upper surface of shaft 77 and the journal at the opposite end of roller 27. Retaining means for roller 27 consists of a bar 86 which is freely retained by brackets 87 at the forward edge of cleats 79 and adapted to vertical and transverse movement. A pin 96 in bar 86 and extending outwardly therefrom is adapted to cooperate with bracket 81 adjacent the upper limit of movement of door 47 and is raised thereby. The lower end of bar 86 is provided with an integral cam shoe 88 having a curved cam surface 89 and a flat bottom 60, this cam shoe operating through a slot 91 formed transversely to the groove 78 and intersecting it. A pin 94 is adapted to engage cam surface 89 as bar 86 is raised, thereby forcing the shoe surface 60 out of engagement with shaft 77. A spring 93 fixed at one end to bar 86 as at 80, has its opposite end fixed to cleat 79 as at 30.

The towel is installed and threaded as indicated, the roll 15 being placed in rack 6 and the end of the towel 65 first brought over the top rear edge 64 thence downwardly, underneath roller 18, thence upwardly be-

tween rollers 18 and 17 as indicated at 20, over and about roll 17, thence downwardly as at 25, under and about roller 27, upwardly as at 49, over roller 24 and between rollers 24 and 23, thence downwardly to be deposited in the lower portion of the cabinet as indicated at 65.

The operation of the device is as follows: Treadle 54 is depressed drawing down tape 56 which rotates pulley 34 in a clockwise direction, viewing Figs. 2 and 3, against the action of tape 61 and spring 63. Coincidentally, pawl 38 engages notch 33 in hub 32 of sprocket 31 rotating sprocket 31 and coincidentally driving sprockets 39 and 41, rotating rollers 17 and 23, which feeds the toweling between rollers 17 and 18, and, 23 and 24, and beneath and about roller 27. Coincidentally, door 47 is raised to its uppermost position, roller 27 being retained in its lowermost position by cam shoe 88, until the final upward movement of door 47 causes bracket 81 to engage pin 96, raising bar 86, causing shoe 88 to be moved back by cooperation of cam surface 89 with pin 94, releasing roller and permitting upward travel by cooperation with cords 83, leaving the loop of toweling free for use and door 47 open.

As treadle 54 is released, spring 63 rotates pulleys 34 in a contra-clockwise direction, pawl 38 dragging backward over hub 32, door 47 closes, drawing roller 27 to its lowermost position by cooperation of brackets 81 with the roller journals until engaged by the bottom of cam shoe 88.

Having described an operative method of constructing and operating the device it will be understood that variations in construction and arrangement which are consistent with the appended claims, may be resorted to without detracting from the spirit or scope of the invention or sacrificing any of its advantages.

What I claim is:

1. A towel cabinet, in combination, a cabinet having an opening at the front thereof and a sliding door for said opening, a frame removably supported in said cabinet, feed rollers journaled in said frame, pressure rollers cooperating with said feed rollers, driving means for driving said feed rollers in one direction, a tension roller mounted adjacent said door, means for positively retaining said tension roller in lowermost position during initial opening movement of said door and releasing means for said retaining means cooperating with said door during the final opening movement thereof, and means cooperating with said driving means for opening and closing said door.

2. In combination, a cabinet, a sliding door mounted in the front of said cabinet, a support for a roll of toweling, treadle operated feeding means for said toweling, a tension roller mounted in grooves adjacent said door,

resiliently urged means for raising said roller, said roller being depressed by brackets on said door when said door is being closed, means for positively retaining said roller in lowermost position while said door is being opened, the final movement of said door cooperating with said retaining means for releasing said roller, and means cooperating with said driving means for opening and closing said door.

In testimony whereof I have affixed my signature.

HERBERT S. McCORMICK.
